UNITED STATES PATENT OFFICE.

SIGMUND JOSEPH, OF NEW YORK, N. Y.

DESIGN FOR A CAKE PAN OR THE LIKE.

Application filed December 16, 1927. Serial No. 24,504. Term of patent 7 years.

To all whom it may concern:

Be it known that I, SIGMUND JOSEPH, a citizen of the United States, and a resident of the city of New York (borough of Manhattan), in the county of New York and State of New York, have invented a new, original, and ornamental Design for a Cake Pan or the like, of which the following is a specification.

I claim:

The ornamental design for a cake pan or the like, as shown.

SIGMUND JOSEPH.
